UNITED STATES PATENT OFFICE.

CHARLES L. HALSTEAD, OF LA CROSSE, WISCONSIN.

HOSE-BAND TIGHTENER.

SPECIFICATION forming part of Letters Patent No. 451,272, dated April 28, 1891.

Application filed May 15, 1890. Serial No. 351,940. (No model.)

To all whom it may concern:

Be it known that I, CHARLES L. HALSTEAD, a citizen of the United States, residing at La Crosse, in the county of La Crosse and State 5 of Wisconsin, have invented certain new and useful Improvements in the Art of Securing Hose-Bands to Metallic Nozzles, Joints, or Couplings, &c.; and I do hereby declare the following to be a full, clear, and exact description 10 of the invention, such as will enable others skilled in the art to which it appertains to make and use the same.

My invention relates to improvements in a device for securing hose-bands; and the object of my invention is to provide a device 15 whereby said bands can be quickly and rigidly secured around the hose, so that the hose will be so closely compressed against the coupling that leakage will be prevented. I attain said 20 object by a certain construction and arrangement of parts fully described in this specification and illustrated in the accompanying drawings, in which—

Figure 1 is a perspective view of my device. Fig. 2 is a similar view showing the device in operation. Fig. 3 is a detail view, 25 partly in section, of the parts which constitute the device. Fig. 4 is a view representing the different phases the band assumes in 30 construction and application.

My invention comprises the thumb-screw D and the plates A and C. The plate A is constructed with the centrally-threaded socket a, in which the thumb-screw D is located and works. In each end of said plate 35 there are the slots a' a', which are adapted to receive and hold the ends b b of the hose-band B.

The plate C is swiveled upon the lower end 40 of the thumb-screw D. This plate is made

with the portion c' cut away, and is concealed upon the under side so as to fit closely against the hose and hold the band in its normal position when the device is being operated. Said portion c' is cut away to provide an 45 opening through which the ends of the band B may pass, and by means of which the same are held in position while the ends b b are being adjusted in the slots a' a' of the plate A and secured around the hose. 50

In applying the band B the same is first bent in a circular form, the ends passing through the loop in the end formed by the cross-bar b'. (See Fig. 4.) The band is then adjusted to the hose and the device applied 55 as shown in Fig. 2. The thumb-screw D is then operated, which draws the band B tightly around the hose. The ends of the band are then bent over by the forward movement of the device, after which the device is removed 60 and the ends of the band bent flatly down, as indicated by the dotted lines in Fig. 4.

What I claim is—

In a device for securing hose-bands, the thumb-screw D, in combination with the plate 65 C, swiveled upon the lower end of said thumb-screw, said plate having the portion c' cut away, and the plate A, having in each end the slots a' a' and provided with a centrally-threaded socket adapted to the thumb-screw 70 D and in which the same works, substantially as described, and for the purpose set forth.

In testimony whereof I affix my signature in presence of two witnesses.

CHARLES L. HALSTEAD.
